UNITED STATES PATENT OFFICE.

WHITE WOLF M. HICKEY, OF SAN FRANCISCO, CALIFORNIA.

MOP-WRINGER.

SPECIFICATION forming part of Letters Patent No. 714,374, dated November 25, 1902.

Application filed July 28, 1902. Serial No. 117,241. (No model.)

To all whom it may concern:

Be it known that I, WHITE WOLF M. HICKEY, a citizen of the United States, residing in the city and county of San Francisco, State of California, have invented an Improvement in Mop-Wringers; and I hereby declare the following to be a full, clear, and exact description of the same.

My invention relates to improvements in mops; and its object is to provide a simple labor-saving device for wringing the mop-cloth.

It consists of a handle having suitable clamp means to engage the ends of the folded mop-cloth, a sleeve slideable on the handle, means for locking the sleeve thereon, a bevel-gear loosely turnable on said sleeve, a rectangular frame carried by said bevel-gear and having its end inclosed by the cloth, and means upon the sleeve by which the said gear and frame

20 may be rotated about the handle as an axis.

Having reference to the accompanying drawings, Figure 1 shows a front view of wringer, partially broken away. Fig. 2 shows a side view of wringer, partially broken away. Fig. 3 shows a section through sleeve and bevel-gear.

30 A represents a mop-handle having suitable clamp means 2 at one end for the engagement of the ends of a centrally-folded mop-cloth 3.

35 A sleeve 4 is slideable on the handle and is adapted to be locked at any desired point thereon by means of a cam-lever 5.

A bevel-gear 6 is loosely turnable on the sleeve and carries a rectangular frame 7, whose outer end passes through the fold of the mop-cloth.

The sides of the frame are slideable in a guide or cross-head 8, turnable on the mop-head.

40 9 is a bevel-gear journaled on the sleeve and meshing with gear 6 and having a crank 10, by which it may be turned.

In operation the mop-cloth is extended, as shown in Fig. 1, by sliding the sleeve carrying the frame toward the mop-head, and the sleeve is locked rigid on the handle by means of the lever-clamp 5. By turning crank 10 the frame is revolved, and as the mop-head end of the cloth remains stationary the cloth

50 is twisted to wring out the water. The crank

is then turned in the opposite direction to bring the frame and cloth into the same plane, the lever 5 released, the sleeve slid upward on the handle to bring the end of the frame against the clamp 2, and the lever 5 again 55 locked, whereupon the cloth is loosened and placed in condition to be used as a mop.

Having thus described my invention, what I claim, and desire to secure by Letters Patent, is—

60 1. A mop-wringer including a non-rotating handle; clamping means at one end thereof adapted to engage one end of the mop-cloth; a sleeve slideable upon the handle; a gear loosely turnable upon and carried by the 65 sleeve; means carried upon the sleeve by which the gear is rotated; a rectangular frame fixed to said gear and adapted to be projected beyond the head end of the handle and to engage the other end of the mop-cloth; a cam- 70 lever carried by and operating through the sleeve for locking the latter to the handle, said lever serving to release the sleeve from its locked position to allow the sleeve and the frame to be rotated relative to the handle and 75 mop-head.

2. A mop-wringer consisting of a non-rotatable handle; a clamp fixed to one end thereof; a centrally-folded mop-cloth the ends of which are brought together and held by said clamp; 80 a cross-head turnable on the mop-head, a sleeve slideable on the handle, provided with a loosely-mounted gear, an engaging gear and a cam-lever said lever operating through the sleeve to engage the handle and lock the sleeve 85 thereto, and to release the sleeve from its locked position; a rectangular frame fixed to the loose gear and having its sides slideable through the ends of the cross-head, and extending along each edge of the mop-cloth, said 90 frame to be projected beyond the end of the handle and mop-head, and means for rotating the frame and cross-head relative to the handle.

95 In witness whereof I have hereunto set my hand.

WHITE WOLF M. HICKEY.
